Primary Examiner — Susan B Hattan*Assistant Examiner* — Brett A Miller(74) *Attorney, Agent, or Firm* — Rankin, Hill & Clark LLP(57) **CLAIM**

The ornamental design for a temporary emergency room, as shown and described.

DESCRIPTION

FIG. 1 is a front view of a temporary emergency room embodying the design;

FIG. 2 is a rear view thereof;

FIG. 3 is a right side view thereof;

FIG. 4 is a left side view thereof;

FIG. 5 is a top plan view thereof;

FIG. 6 is a bottom view thereof;

FIG. 7 is a perspective view thereof;

FIG. 8 is a first enlarged portion of the perspective view of FIG. 7;

FIG. 9 is a second enlarged portion of the perspective view of FIG. 7; and,

FIG. 10 is a third enlarged portion of the front view of FIG. 1.

The broken lines in the drawings illustrate borders of enlarged views and form no part of the claimed design.
